ROCKET TOY BANK

Carl F. Peterson, Detroit, Mich., assignor to Duro Mold
and Manufacturing, Inc., Detroit, Mich.

Application February 9, 1959, Serial No. 54,509

Term of patent 7 years

(Cl. D34—5)

Fig. 1 is a front elevational view of a rocket toy bank, showing my new design;

Fig. 2 is a left side elevational view;

Fig. 3 is a right side elevational view;

Fig. 4 is a top plan view; and

Fig. 5 is a rear elevational view with the rocket broken away for convenience of illustration.

I claim:

The ornamental design for a rocket toy bank, as shown and described.
